(74) Attorney, Agent, or Firm — Rothwell, Figg, Ernst & Manbeck, P.C.

(57) CLAIM

The ornamental design for a sandal shoe, as shown and described.

DESCRIPTION

FIG. 1 is a front left perspective view of a sandal shoe showing my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The portions of the sandal shoe shown in dot-dash broken lines in FIGS. 1-3 and 7 form no part of the claimed design. The portions of the sandal shoe shown in even-dashed broken lines in FIGS. 1-6 represent thread stitching and do form part of the claimed design.
